UNITED STATES PATENT OFFICE.

JOHN H. SCHEIBELER, OF NEBRASKA CITY, NEBRASKA.

PLANING MACHINE.

Application filed June 29, 1923. Serial No. 648,628.

The invention relates to planing machines, and has for its object to provide a device of this character whereby tapered articles such as wagon poles and fence posts may be 5 formed and planed on both sides simultaneously.

A further object is to provide a planing machine comprising vertically disposed cutter heads, one of which heads is yieldably mounted thereby allowing the heads to spread apart as a piece of material is fed therebetween on a template, guidable between rollers carried by the cutterhead shafts, which template spreads the cutterhead according to the taper of the template. 10

A further object is to provide horizontally disposed feed rollers located forwardly and rearwardly of the cutter heads and adjacent the top of the table for feeding the 20 template and material between the cutterheads. Also to provide guide rollers above the feed rollers, yieldably mounted for preventing upward tilting of the template and material being planed during the planing 25 operation.

A further object is to provide means whereby the feed rolls and the cutterheads may be rotated from a single source of power. 30

With the above and other objects in view the invention resides in the combination and arrangement of parts as hereinafter set forth, shown in the drawing, described and claimed, it being understood that changes 35 in the precise embodiment of the invention may be made within the scope of what is claimed without departing from the spirit of the invention.

In the drawing:—

40 Figure 1 is a side elevation of the machine.

Figure 2 is a horizontal sectional view taken on line 2—2 of Figure 1.

45 Figure 3 is a top plan view of the front end of the machine, showing the upper guide rollers removed.

Figure 4 is a transverse sectional view through the machine taken on line 4—4 of Figure 3.

50 Figure 5 is a perspective view of one of the guide slides for one of the cutterhead shafts.

Figure 6 is a perspective view of one of the guide roller supporting brackets.

55 Referring to the drawing, the numeral 1 designates a table top and 2 the supporting

legs therefor. Extending transversely and beneath the table top 1 is a bar 3, which bar is provided with spaced bearings 4 and 5. The bearing 4 is stationary, while the bearing 5 is carried by a transversely movable dovetailed slide 6, which is slidably mounted in the channel 7 of the bar 3, therefore it will be seen that the shafts 8, which extend vertically through the bearing members 4 and 5 may assume positions at different distances from each other against the action of the coiled spring 9 carried by the bearing member 5, consequently the cutters 10, during the feeding of a piece of material therebetween may move in relation to each other according to the size of the piece of material being cut. When it is desired to plane a piece of material into a tapered shape, such for instance as for a wagon pole or a fence post, a template 11 is placed between the rollers 12, which are rotatably mounted on the shafts 8, with the piece of material on the top of the template between the cutter heads 10. As the tapered template is 70 forced inwardly it is obvious that the cutter heads will be forced outwardly in relation to each other cutting the piece of material on opposite sides thereof into a tapered form of the same shape as the template, 75 thereby not only forming a piece of material in tapered form but planing both sides thereof simultaneously. The movable bearing 5 is provided with brackets 13 in the ends of which the ends of the shafts 8 are 80 rotatably mounted, thereby bracing said shafts and preventing springing thereof during a planing operation. The ends of the other shaft 8 are braced by twisted braces 14, which are preferably carried by 85 the transversely disposed bar 3. Secured to the lower ends of the shafts 8 are pulleys 15, around which pulleys endless belts 16 extend, which belts extend rearwardly under the table top 1 and over a drive pulley 17 90 which is carried by the drive shaft 18. It will be seen that when the drive shaft 18 is rotated from any suitable source of power belted to the pulley 19, the cutter heads 10 will be simultaneously rotated, thereby insuring a planing operation on both sides of the piece of material disposed between the cutterheads 10. Extending transversely of the machine beneath the top 1 are shafts 21, 95 which shafts are located at opposite sides of the vertically disposed cutter shafts 8, and are provided with feed rollers 22, which

feed the template between the cutterheads and insure the accurate feeding of the template and piece of material being cut by the cutterheads 10. However to additionally 5 guide the piece of material being cut in its longitudinal movement during a cutting operation, the guide rollers 23 are provided, which guide rollers having their pintles 24 rotatably mounted in slideable bearing blocks 10 25 in vertically disposed brackets 26. The bearing blocks 25 are normally pulled downwardly by means of tension springs 27, and consequently the guide rollers 23 are pulled 15 downwardly into engagement with the upper side of the piece of material being passed through the cutterheads thereby guiding the same. If so desired the bearing blocks 25 may be held in any desired position by means of pins 28 which may be 20 passed through any of the apertures 29 beneath the bearing blocks 25.

The drive shaft 18 is provided with a worm 30, which meshes with a worm gear 31 carried by the longitudinally disposed shaft 25 32, which shaft 32 is in turn provided with worms 33, which mesh with worm gears 34 carried by the transversely disposed feed roller shafts 21, therefore it will be seen that 30 the same source of power is utilized for rotating the cutter heads 10 and the feed rollers 22.

From the above it will be seen that a planing machine is provided which is particu-

larly adapted for simultaneously planing 35 opposite sides of a piece of material into a tapered form, or in any other form according to the shape of the template used. It will also be seen that all of the mechanism of the machine is operated from a single 40 source of power.

The invention having been set forth what is claimed as new and useful is—

A planing machine comprising a table, a vertically disposed fixed shaft rotatably mounted in the bearing of said table, a vertically disposed movable shaft extending through a slot in the table and in parallel relation to the first mentioned shaft, cutter heads carried by the shafts above the table, a transversely disposed bar beneath the table and having a crosshead guide therein, a crosshead block slidably mounted in the guide, and in a bearing of which the movable shaft is rotatably mounted, a coiled 55 spring disposed within the crosshead and forming means for forcing the same towards the first mentioned shaft, driving connections carried by the lower ends of the shafts, brace arms connecting the ends of the movable shaft and the crosshead, one of 60 which brace arms extends through the slot in the table.

In testimony whereof I hereunto affix my signature.

JOHN H. SCHEIBLER.
